South Bend, Ind., a corporation of Delaware

Application October 15, 1949, Serial No. 121,493

10 Claims. (Cl. 123—25)

1

The present invention relates to a fuel system for internal combustion engines, and more particularly to a control mechanism for fuel metering devices such as those disclosed in U. S. Patent 2,452,627 issued on November 2, 1948, and application Serial No. 751,288 filed May 29, 1947. Fuel metering devices of the type disclosed in said patent and application basically deliver fuel to the engine at a rate directly proportional to the speed of the engine and consequently deliver fuel proportionally to the theoretical maximum volumetric efficiency of the engine. It is, therefore, seen that if the fuel delivery is not corrected to allow for the decrease in volumetric efficiency of the engine, particularly at the higher speeds, the fuel-air ratio would become richer, perhaps to a point where engine performance and economy would be appreciably affected. The present invention, therefore, has as its principal object to provide a control mechanism for correcting the fuel delivery in the aforementioned fuel metering devices to compensate for the decrease in volumetric efficiency of the engine, particularly at the higher speeds. Another object of the invention is to provide a control mechanism for a fuel system for varying the fuel delivery in accordance with engine requirements. Further objects and advantages of the present invention will become apparent from the following description taken in conjunction with the accompanying drawing, wherein one embodiment of our invention is shown schematically in combination with a fuel metering device of the type disclosed in the aforementioned patent and application.

Referring more specifically to the drawing, numeral 10 designates the main body of the fuel metering device, 12 a throttle valve, 14 an air inlet, and 16 a mixture outlet of the induction passage for an internal combustion engine (not shown). Fuel is supplied to the metering device through a conduit 18 from a source such as a pump or tank (not shown) at a substantially constant pressure and is delivered through conduit 20 to the inlet of a centrifugal pump 22 which delivers the fuel at an increased variable pressure through conduit 24, main metering orifice 26, conduit 28, chamber 30 and fuel discharge nozzle 32 to the induction passage on the engine side of the throttle valve. The pressure in said chamber is regulated by a valve 33 which is controlled by a flexible diaphragm 34 and is adapted to seat on the inlet of nozzle 32. The effective size of the main metering orifice is controlled by a valve 35, such as the one disclosed in application Serial No. 747,113 filed May 9, 1947.

The centrifugal pump 22 consists of a fuel chamber 36 and an impeller 38 mounted on shaft 40 which is journaled in pump housing 42 and is adapted to be driven by the engine through a shaft, cable or the like connected to the reduced

2

portion 44 of shaft 40. On the intake side of the centrifugal pump is a vapor bleed 46 which is connected by a conduit 48 to the fuel supply tank to prevent vapor locking of the pump, particularly when the engine is operating under high temperature conditions.

During the operation of the engine, the pressure in conduit 24 is at all times greater than the inlet pressure of pump 22 by an amount directly proportional to the square of the impeller speed, and since the impeller is driven at engine speed, the increase in pressure is directly proportional to the square of engine speed. The pressure in conduit 28 and chamber 30 during engine operation is always less than the pressure in conduit 24, the differential in the pressures being the effective metering head across metering orifice 26. The pressure in chamber 30 is determined by the pressure maintained in chamber 50 which is separated from chamber 30 by flexible diaphragm 34 and valve 33, said valve being adapted to move to and from the inlet end of nozzle 32 to vary the capacity of said inlet as the pressure increases and decreases in chamber 50, thus increasing and decreasing the pressure in chamber 30 to correspond to that in chamber 50.

Chamber 50 is connected with passage 20 on the anterior side of the impeller by a conduit 52 having a restriction 54 opening directly into chamber 50 and with conduit 24 on the posterior side of said impeller by conduit 56, orifice 58, chamber 60 and conduit 62. The pressure of the fuel in conduit 56 and chamber 50 is controlled by a tapered valve 64 in orifice 58 connected to or formed integrally with a fluted valve stem 66 which is slidably received in a spring 68 and secured at its outer end to a flexible diaphragm 70 and stiffening members 72 and 74. The chamber 60 is connected directly with the impeller outlet pressure in conduit 24 by conduit 62 and is, therefore, subjected to the unmetered fuel pressure which constantly urges diaphragm 70 in the direction to open valve 64.

With the fuel flowing through orifice 58, passage 56, chamber 50 and orifice 54, a pressure is created in chamber 50 of a value intermediate the unmetered fuel pressure in conduit 24 and the impeller inlet pressure in passage 20, the value of this intermediate pressure depending upon the relative sizes of orifices 54 and 58. Consequently, if orifice 58 has an effective area equal to that of orifice 54, the pressure in chamber 50 will remain substantially half-way between the pressure of the unmetered fuel in conduit 24 and the pressure of the fuel in conduit 20 anterior to the impeller irrespective of variations in impeller speed.

The position of valve 64 in orifice 58 is controlled in accordance with the position of the

throttle valve 12 through a spring 80 and a cam 82 secured to the throttle valve shaft 84 and in accordance with the speed of the engine through the pressure of the fuel on the outlet side of the impeller transmitted through conduit 62 to chamber 60. The contour of cam 82 is such that the effective area of orifice 58 is decreased by the opening movement of throttle valve 12. It is seen that when the throttle valve is moved in the opening direction, the effective size of orifice 58 is restricted to an effective area less than that at closed throttle by tapered valve 64 so that the pressure in chamber 50 more nearly approaches the impeller inlet pressure. As a result of the unbalanced condition created between chambers 30 and 50 as the throttle valve is opened, diaphragm 34 moves toward chamber 50 and away from the inlet of discharge nozzle 32, permitting a greater discharge of fuel into the induction passage. When the throttle valve is moved in the closing direction, the effective area of orifice 58 is increased, causing the pressure of the fuel in chamber 50 temporarily to exceed that of the fuel in chamber 30. The diaphragm 34 and valve 33 consequently move toward the nozzle inlet, restricting the discharge of fuel from chamber 30 so that the pressure in said latter chamber increases until it becomes equal to the pressure in chamber 50. Further, in the event the pressure of the metered fuel in chamber 30 should tend to exceed the pressure of that behind the diaphragm 54, as a result of increased fuel delivery by the impeller, the diaphragm will move away from the nozzle inlet, permitting the excess fuel to discharge into the induction passage at an increased rate such that the pressures on either side of the diaphragm will again become substantially equalized.

The position to which valve 64 is moved during the movement of the cam 82 is modified by the pump outlet pressure transmitted through conduits 24 and 62 to chamber 60 so that as the pump outlet pressure increases with an increase in engine speed, diaphragm 70 is moved downwardly, as shown in the drawings, in the direction to open valve 64. The opening of valve 64 causes the pressure in chamber 50 to increase and urge valve 33 toward closed position and limit the flow of fuel to the engine to compensate for the decrease in the volumetric efficiency of the engine, particularly at the higher engine speeds.

In the present fuel metering device, an increase in fuel supply pressure causes a corresponding increase in the fuel pressure throughout the entire system; consequently, in order to prevent a general increase in pressure throughout the system from opening valve 64 and thereby leaning out the fuel-air mixture, a chamber 90 connected to the fuel inlet conduit 18 by conduit 92 maintains the pressure on the lower side of diaphragm 70 at a value which is at all times equal to the fuel supply pressure. By this arrangement, for any given impeller speed, a constant differential is maintained across said diaphragm regardless of any variations in the fuel supply pressure. A diaphragm 94 forms the lower wall of chamber 90 adjacent cam 82 to permit the action of said cam to be transmitted through spring 80 to valve 64. The calibration of spring 80 may be selected to give the desired correction in fuel delivery for any particular engine.

When the engine becomes inoperative and the impeller is no longer pumping fuel from conduit 20 into conduit 24 and thence into chamber 30,

the pressures of the fuel in chambers 30 and 50 remain substantially equal to one another, permitting diaphragm 34 in effect to float between the two chambers. Thus, if no means were provided to prevent fuel from discharging into the induction passage, a small quantity of fuel would seep between the valve 33 and the inlet of discharge nozzle 32 and might in time flood the engine. To prevent this, a spring 98 is placed behind a diaphragm 100 to urge said diaphragm against diaphragm 34 and thereby to seat valve 33 over the inlet of nozzle 32. Under certain engine operating conditions, the temperature may become so high that the absolute fuel pressures in the system and consequently in chambers 30 and 50 will increase to a point where spring 98 alone could not seat said valve over the inlet of discharge nozzle 32 when the engine is shut off. To offset such high pressure in chambers 30 and 50, the tank pressure is transmitted through conduits 48 and 102 to chamber 104 in which spring 98 is located. Thus, when the engine is inoperative, the pressures in the three chambers are equalized so that the effective force of spring 98 is always sufficient to seat valve 33.

30 We claim:

1. In a fuel supply system for an engine having an induction passage with a throttle therein: a conduit having a discharge nozzle in said induction passage; a means for varying the pressure of the fuel in said conduit in accordance with engine speed; a metering orifice in said conduit posterior to said pressure varying means; a discharge valve between said orifice and said nozzle; a passageway having two spaced restrictions therein communicating with the conduit anterior and posterior to said pressure varying means for creating a control pressure; a member responsive to metered fuel pressure and to said control pressure, for regulating said discharge valve; and a means responsive to the movement of the throttle and to the pressure in said conduit between said pressure varying means and said metering orifice for varying the effective size of one of said restrictions.

50 2. In a fuel supply system for an engine having an induction passage with a throttle therein: a conduit having a discharge nozzle in said induction passage; a means for varying the pressure of the fuel in said conduit in accordance with engine speed; a discharge valve between said pressure varying means and said nozzle; a passageway having two spaced restrictions therein communicating with the conduit anterior and posterior to said pressure varying means for creating a control pressure; a member responsive to said control pressure for regulating said discharge valve; and a means responsive to the movement of the throttle and to the pressure on the downstream side of said pressure varying means for varying the effective size of one of said restrictions.

70 3. In a fuel supply system for an engine having an induction passage: a conduit having a discharge nozzle in said induction passage; a means for varying the pressure of the fuel in said conduit in accordance with engine speed; a discharge valve between said pressure varying means and said nozzle; a passageway having two spaced restrictions communicating with the conduit anterior and posterior to said pressure varying

means for creating a control pressure; a member responsive to said control pressure for regulating the discharge valve; a control valve for varying the effective size of one of said restrictions; a yieldable means for urging said control valve toward closed position; and a pressure responsive means adapted to be subjected to the pressure on the downstream side of said pressure varying means for urging said valve toward open position.

4. In a fuel supply system for an engine having an induction passage; a conduit having a discharge nozzle in said induction passage; a means for varying the pressure of the fuel in said conduit in accordance with engine speed; a metering orifice in said conduit posterior to said pressure varying means; a discharge valve between said orifice and nozzle; a passageway having two spaced restrictions therein communicating with the conduit anterior and posterior to said pressure varying means for creating a control pressure; a member responsive to metered fuel pressure and to said control pressure for regulating said discharge valve; a control valve for varying the effective size of one of said restrictions; a yieldable means for urging said control valve toward closed position; and a pressure responsive means operatively connected to said control valve and adapted to be subjected to the pressure on the downstream side of said pressure varying means and in the valve opening direction to the pressure posterior to said pressure varying means and in the valve closing direction to the pressure on the anterior side of said pressure varying means.

5. In a fuel metering device for an engine having an induction passage with a throttle therein; a conduit for delivering fuel from a source to said induction passage; an impeller in said conduit having a fuel inlet and a fuel outlet; a discharge valve in said conduit on the outlet side of said impeller; a passageway communicating with said conduit on the inlet and outlet sides of said impeller and having two spaced restrictions therein; a pressure responsive means adapted to be subjected to the pressure existing between said restrictions for controlling said discharge valve; and a means responsive to the movement of the throttle and to the pressure on the outlet side of said impeller for varying the effective size of one of said restrictions.

6. In a fuel metering device for an engine having an induction passage with a throttle therein; a conduit for delivering fuel from a source to said induction passage; an impeller in said conduit having a fuel inlet and a fuel outlet; a discharge valve in said conduit on the outlet side of said impeller; a passageway communicating with said conduit on the inlet and outlet sides of said impeller and having two spaced restrictions therein; a pressure responsive means subjected to the pressure existing between said restrictions for controlling said discharge valve; a control valve for varying the effective size of one of said restrictions; a yieldable means for urging said control valve toward closed positions; and a pressure responsive means adapted to be subjected to the pressure on the outlet side of said impeller for urging said valve toward open position.

7. In a fuel metering device for an engine having an induction passage; a conduit for delivering fuel from a source to said induction passage; an impeller in said conduit having a fuel inlet and a fuel outlet; a metering orifice in said con-

duit on the outlet side of said impeller; a discharge valve in said conduit on the downstream side of said metering orifice; a passageway communicating with said conduit on the inlet and outlet sides of said impeller and having two spaced restrictions therein; a pressure responsive means subjected to the pressure existing between said restrictions for controlling said discharge valve; a control valve for varying the effective size of one of said restrictions; a yieldable means for urging said control valve toward closed position; and a pressure responsive means operatively connected to said control valve and adapted to be subjected to the pressure on the downstream side of said impeller and in the valve closing direction to the pressure on the upstream side of said impeller.

8. A fuel metering device comprising a fuel supply conduit having in series therein an impeller, a metering orifice, and a discharge valve; a passageway communicating with said conduit anterior and posterior to said impeller and having two restrictions therein; a means responsive to the pressure between said restrictions for controlling said discharge valve; a control valve for varying the effective size of one of said restrictions; a yieldable means for urging said control valve toward closed position; and a pressure responsive means adapted to be subjected to the pressure on the downstream side of said impeller for urging said control valve toward open position.

9. A fuel metering device comprising a fuel supply conduit having in series therein an impeller, a metering orifice, and a discharge valve; a passageway communicating with said conduit anterior and posterior to said impeller and having two restrictions therein; a means responsive to the pressure between said restrictions for controlling said discharge valve; a control valve for varying the effective size of one of said restrictions; and a pressure responsive means operatively connected to said control valve and adapted to be subjected to the pressure posterior to said impeller and in the valve closing direction to the pressure anterior to said impeller.

10. A fuel metering device comprising an induction passage having a throttle therein; a fuel supply conduit having in series therein an impeller, a metering orifice, and a discharge valve; a passageway communicating with said conduit anterior and posterior to said impeller and having two restrictions therein; a means responsive to the pressure between said restrictions for controlling said discharge valve; and a means responsive to the movement of said throttle and to the pressure between said impeller and said metering orifice for varying the effective size of one of said restrictions.
